UNITED STATES PATENT OFFICE.

WILLIAM A. ENGLAND, OF SAN FRANCISCO, CALIFORNIA.

BARREL STRUCTURE.

Application filed January 22, 1921. Serial No. 439,124.

To all whom it may concern:

Be it known that I, WILLIAM A. ENGLAND, a citizen of the United States, and a resident of the city and county of San Francisco and State of California, have invented a new and useful Barrel Structure, of which the following is a specification.

My invention relates to barrel structures and especially to those in which an inner receptacle is disposed.

An object of the invention is to provide an improved means for mounting a receptacle in an exterior casing comprising a barrel. Another object is to provide means for preventing warping of the exterior casing or barrel.

My invention possesses other objects and features of advantage, some of which, with the foregoing, will be set forth in the following description of my invention. It is to be understood that I do not limit myself to the showing made by the said description, as I may adopt variant forms of my invention within the scope of the claims.

In the drawings, Fig. 1 is an elevation of one embodiment of my invention. Fig. 2 is a top view of the barrel structure.

A desirable method of serving certain beverages, such for instance as root beer, is from a container having the outward appearance of a barrel. Within the barrel is a receptacle into which containers for the beverage are disposed and surrounded by ice. Suitable connections to a faucet in the side of the barrel provide means for drawing off the beverage as it is wanted. Considerable difficulty has been experienced with the barrels in the structure just referred to because of warping in the open upper end. The method of securing the inner receptacle, too, has not been satisfactory. It is therefore to remedy these two troubles, among others, that I have provided the instant structure, which comprises a strong wooden barrel 2 provided with the loose

cover 3. The upper end on the inside is formed with an annular groove preferably of a section substantially that shown in Fig. 1, and a rigid hoop or ring 4 of metal is disposed in the groove. The ring is sufficiently heavy to resist distortion and its effect is to keep the barrel round and true at its upper end.

The receptacle on the inside of the barrel is formed with inner and outer walls, 6 and 7 respectively so that the space between may be vacuumized, the better to preserve the low temperature desired in the receptacle. The inner wall 6 is the diameter of the opening of the ring and is formed with an outwardly extending flange 8 which is attached to the upper face of the ring by solder or other suitable means. The outer wall 7 is provided with an inwardly extending flange 8, the opening thru which is the same as the diameter of the inner wall. This flange is seated on the lower face of the annular bracing ring, and similarly attached thereto. Thus a very strong and compact receptacle is secured and one in which a bracing means for the barrel casing is included.

I claim:

1. A barrel structure comprising a barrel, a rigid hoop engaging one end of the barrel on the inside, and a receptacle pendently disposed on said hoop.

2. A barrel structure comprising a barrel, a rigid annular ring engaging one end of the barrel on the inside, a double walled receptacle pendently disposed on said ring, a flange on the inner wall of said receptacle overlying the upper face of said ring and connected thereto, and a flange on the outer wall of said receptacle underlying the lower face of said ring and connected thereto.

In testimony whereof, I have hereunto set my hand.

WILLIAM A. ENGLAND.
